UNITED STATES PATENT OFFICE.

EUGENE A. WHORLEY, OF ROANOKE, VIRGINIA.

PAPER-BAG HOLDER.

1,281,241.

Specification of Letters Patent.

Patented Oct. 8, 1918.

Application filed July 18, 1918. Serial No. 245,510.

To all whom it may concern:

Be it known that I, EUGENE A. WHORLEY, a citizen of the United States, residing at Roanoke, in the county of Roanoke and 5 State of Virginia, have invented a new and useful Paper-Bag Holder, of which the following is a specification.

This invention relates to paper bag holders, and more particularly to that class of 10 devices designed to hold packs of paper bags of different sizes.

The object is to provide a simple and easily constructed holder which will securely hold in separated packs a large number 15 of bags, so that it is possible to extract one or more bags of a certain size, without interfering with the bags of another size in adjacent packs.

Another object is to provide a holding 20 device of this character which will hold the packs of folded bags in such manner as to always present one edge of the folded bottom of the bag in a vertical position to be easily grasped by the hand of the operator 25 in extracting the same.

A further object is to provide improved 30 means for clamping the bags in place, and for imparting such clamping action to the bags until the last one thereof is extracted, and to form such clamping means in a manner 35 to facilitate the introduction of the packs of bags when loading the holder.

A full and complete understanding of the 40 invention may be obtained from a consideration of the following detailed description, taken in connection with the accompanying drawing forming a part of this specification; it being understood that while the drawing shows a practical form of the invention, the latter is not confined to strict 45 conformity therewith, but may be changed or modified, so long as such changes or modifications mark no material departure from the salient features of the invention, as specifically pointed out in the appended claim.

In the drawing, in which like reference characters designate similar parts throughout the several figures:—

50 Figure 1 is a side elevation of the improved bag holder, each compartment being

shown as containing a pack of folded paper bags;

Fig. 2 is a vertical longitudinal section of the upper portion thereof with the bags 55 omitted;

Fig. 3 is a detail transverse section taken on the line 3—3 of Fig. 2.

The device of the present invention is designed to overcome the great inconvenience 60 encountered in grocery and other stores, where the ordinary paper bags in common use are simply placed on a counter or other support, or, as is sometimes done, are placed in individual receptacles with no means for 65 clamping the same therein when, in either case, the bags are separated and scattered about, thus resulting in the mixing of the several sizes and in the loss of time and labor.

70 The desired results are obtained by providing a separate compartment for each pack of a different size of bag, and having means for clamping and holding the same in such position as to expose the free side 75 edge of the folded bottom of the bag, which may be readily grasped to remove the same and not interfere with the next adjacent bag beneath, which operation may be repeated until the compartment is entirely emptied. 80

The improved device comprises a frame formed of a pair of spaced side plates 1—1, composed of some suitable sheet metal, secured, as by crimping or in any other desired manner, to suitable feet or base pieces 85 2—2, which are also composed, preferably, of metal, and are so folded or otherwise formed as to be securely fastened to the bottom edges of the side plates.

90 The side plates are considerably higher than they are wide and are each formed to provide a perpendicular rear edge 3, an inclined front edge 4, and a top edge 5 which is somewhat less in length than the bottom of the side plates where joined to the foot 95 or base piece 2.

The spaced side plates 1—1 are inclined toward each other at their tops, and are there joined by a top plate 6, which is secured to the side plates in any desired manner, and the front, rear and top edges of the latter are preferably provided with strength-

ening ribs 7 formed by bending the metal back upon itself.

By reason of the inclination of the side plates toward each other, provision is made 5 for the difference in the width of the bags, it being designed to support the larger bags at the bottom of the device and decreasing in size toward the top thereof.

Individual bag holders, adapted to different size bags, are supported between the side plates, one above the other and in 10 spaced relation. Each holder is composed of a single piece of sheet metal bent at an intermediate point to form a spring loop 8 and a flat bottom plate or supporting member 9, having integral, depending ears 10-10 on each side, which are adapted to be secured by rivets 11-11 or other fasteners, in a 15 position to support the bottom plate 9 in an inclined position between the side plates 1-1. The spring loop 8 terminates, on the other side, in a presser plate 12 which has a normal tendency toward the bottom plate 9 and terminates at its free end, in an up- 20 and wardly curved terminal portion 13, which freely admits the introduction of a pack of folded bags between the presser plate and the bottom plate, as will be readily understood. The spring loops 8 of the several bag 25 holders are arranged at the rear perpendicular edges of the side plates 1-1 and extend somewhat beyond the same, while the upwardly curved terminal portions 13 of the presser plates extend forwardly and beyond 30 the front inclined edges 4-4 of the said side plates, as is clearly shown in the drawing.

The lower, front terminal portions of the bottom plates 9 are each curved downwardly 40 and rearwardly, as indicated at 14, and thence bent to form forwardly directed horizontally disposed portions 15 defining substantially horizontal bottom walls to pockets 16, and terminating in upwardly disposed 45 substantially vertical front walls 17, having marginal strengthening beads 18 formed at their upper edges and extending from side to side of the said front wall 17.

Each pocket 16 decreases in size upwardly, 50 in accordance with the decrease in the size and proportions of the several holding devices, and the said pockets are adapted to lie within and above the curved terminal portion 13 of the next adjacent presser plate below, and to be spaced away therefrom to permit the latter to spring upwardly 55 a sufficient distance to allow of the introduction of a pack of bags.

The pockets 16 are specially shaped to receive 60 the bottoms of the bags which are folded in the ordinary manner. The bottom of the bags form the most bulky part of the pack, so that ample room must be provided therefor. The vertical front wall 17, in con-

nexion with the horizontal bottom wall 15, 65 retains the pack in a position so that the upstanding edge A of the bottom portions of the bags B are always held in a vertical position so as to be easily grasped for removal, as indicated in Fig. 1 of the drawing. 70

The inner curved wall 14 provides for the expansion of the pockets and allows for a greater number to be inserted than would be the case if the wall were straight. 75

The bag holders are secured to the frame plates 1 at a single point between the front and rear edges, but nearer the front edge. This allows greater freedom for the loops 8 which provide the spring for imparting 80 elasticity to the presser plates 12.

It will be seen upon reference to Fig. 3, that the presser plates 12 are of nearly the same width as the bag supporting members 9, a slight space being provided between 85 each side edge of the plates 12 and the frame plates 1 to allow for the vertical movement of said presser plates.

As shown in Fig. 2, the presser plates normally contact with the bag supporting members at a point in rear of the terminal portions 13. When the bag holders are filled, the presser plates 12 move away from the bottom plates 9, and these two elements engage the bags throughout the greater portion of the lengths of the bags, and not at a single point as in some bag holders. 90

The frame plates 1 provide side walls for the bag holders so as to retain the bags therein and prevent their moving laterally. 100

What is claimed is:—

A bag holder comprising spaced side plates constituting standards, a plurality of individual bag holders disposed between the standards, from the base to the top, each bag holder being formed of a single piece of sheet metal, of a width substantially equal to the distance between the standards, and bent intermediate of its ends to form a spring loop, a bottom bag supporting member, and an upper presser plate, the bags being inserted between said member, said plate and said standards, the latter holding the bags from shifting laterally, means for fastening the bag holders to the inner sides of the standards, said means being applied to the bag supporting members, each bag supporting member having a pocket formed at the lower end projecting beyond the front edges of the standards and adapted to receive the folded bottoms of a pack of bags, each pocket consisting of a curved inner wall, a substantially horizontal bottom wall and a substantially vertical front wall, whereby the bottom of each bag is maintained in a position to project the free edge of said bottom substantially vertical, and the said presser plate being normally in con- 115
120
125

tacting relation with the bottom supporting member near the front end and receding therefrom upon the insertion of the bags, the front terminal of each presser plate being
5 curved upwardly beneath the pocket of the next adjacent bag holder.

In testimony, that I claim the foregoing as

my own, I have hereto affixed my signature in the presence of two witnesses.

EUGENE A. WHORLEY.
